UNITED STATES PATENT OFFICE

FRANCIS I. DU PONT, OF WILMINGTON, DELAWARE

INSTRUMENT BOARD FOR AUTOMOBILES

Application filed February 9, 1927. Serial No. 166,962.

My invention relates to an improvement in instrument boards for automobiles and more particularly to means whereby the instruments may be efficiently illuminated at night

5 without the production of any glare tending to interfere with the vision of the operator.

As is well known the several instruments, as an oil gauge, ammeter, speedometer, etc., necessary for indicating conditions during the 10 operation of an automobile, are usually mounted on an instrument board positioned in front of the operator, and it is quite customary to group the instruments, the group being positioned behind a pane or sheet of glass 15 let into the instrument board. In order that the instruments may be visible to the operator of an automobile at night, it is customary to provide a lamp so positioned as to throw light on the instruments. However, as is well 20 known, the lamp, if positioned to effectively light up the instruments, also causes more or less glare with the result that the operator's vision ahead is materially impaired.

Heretofore numerous efforts have been 25 made to avoid the glare from the so-called dash light, but such have been substantially unsuccessful, it having been found that where glare has been reduced the uniform and effective lighting of the instruments has been 30 correspondingly reduced.

Now it is the object of my invention to provide means whereby the instruments carried by the instrument board of an automobile may be uniformly and efficiently illuminated 35 without the production of glare.

Having now indicated, in a general way, the nature and purpose of my invention, I will proceed to a detailed description thereof with reference to the accompanying drawings in which I have illustrated a preferred 40 embodiment and in which:—

Fig. 1 is a front view of an instrument board embodying my invention, the end portions being broken away.

45 Fig. 2 is a sectional view on line 2—2, Fig. 1.
Fig. 3 is a sectional view on line 3—3, Fig. 1.

In the drawings *a* indicates an instrument board such as is usually provided in an automobile. The board *a* is provided with a recess of any desired shape, for example, an

elliptical recess as shown in Figure 1, into which is fitted a sheet or plate *b* of glass, suitable means being provided for retaining the plate in place.

The plate of glass *b*, preferably of elliptical shape and the edges of which are preferably silvered as indicated at *x*, Figs. 2 and 3, or otherwise made reflective, is provided adjacent its upper edge and midway between its ends with an aperture *c* in which is positioned an electric lamp *d*, mounted in a socket *e*, extending through a suitable aperture in and supported by the instrument board. The lamp is connected to an electric circuit through wires *f*. The wall of the aperture *c* may be cylindrical, though it is preferable that it be made tapering for a distance from the front and back of the plate, as shown at *y*, Fig. 2, and cylindrical in the central portion, as shown at *z*, Fig. 2. The tapered portions 70 of the wall of the aperture *c* are at such an angle that rays from the lamp entering the body of the plate *b* will extend in directions such that they will strike the face of the plate at angles of total reflection. The front of the 75 aperture *c* is closed by means of a cover *g* pivotally attached to a casing *h* provided with spring lugs *i* adapted to extend into the aperture and engage the wall thereof to maintain the casing and cover in position.

In the rear face of plate *b* below the aperture *c*, is formed a relatively circular recess *j*, the walls of which are vertical and the bottom of which is convex, as shown at *k*, Fig. 2. On opposite sides of the aperture *c* are formed 85 relatively small circular recesses *j'* having vertical walls and convex bottoms *k'*, while adjacent the recesses *j'* are formed further circular recesses *j''* having vertical walls and convex bottoms *k''*. The recesses *j''* are made 90 deeper than the recesses *j'*, which are positioned between the recesses *j''* and the aperture *c* in which is positioned the lamp *d*.

Various instruments extend through suitable apertures formed in the instrument 95 board *a* in line with the several recesses and are supported by the board in line with the apertures and immediately adjacent the rear face of the plate *b*. For example, a speedometer *l* is supported with its dial concentric 100

with the recess *j*, while, for example, an oil pressure gauge *m* and a clock *n* are supported with the dials in line with the recesses *j'* and, for example, an ammeter *o* and a gasoline gauge *p* are supported with their dials in line with the apertures *j''*.

Against the rear face of the plate *b* is positioned a mat *q*, apertured in line with the several recesses. The mat *q* may be of any desired material, a paper or cloth and is preferably black, or of a color which will contrast with the dials of the instruments.

In the operation of the embodiment of my invention above described, if the lamp *d*, which is positioned in the aperture *c* in the glass plate *b*, be lighted, the rays therefrom will be prevented from extending forwardly by the cover *g* and from extending rearwardly by the socket *e*. Thus the effective rays emanating from the lamp will strike the wall of the aperture *c* in the plate and will pass therethrough into the body of the plate. Since the wall of the aperture *c* is tapered adjacent the front and rear faces of the plate, those rays which pass through the wall of the aperture adjacent the faces of the plate will, due to the angularity of the tapered surfaces of the wall, pass into the body of the plate in a direction such that they will respectively strike the faces of the plate at an angle at which on tending to pass from a denser medium, the plate, to a lighter medium, the atmosphere, they will be totally reflected from the surface back into the body of the plate. Should any of the rays from the lamp tend to pass out of the sheet adjacent the forward end of aperture *c*, such will be masked by the casing *h* and the extension of rays from the front of the plate will be prevented. The rays from the lamp reflected from the faces of the plate will travel longitudinally through the body of the plate, being reflected from face to face. The rays from the lamp which strike the cylindrical central portion of the wall of the aperture will travel longitudinally of the plate. Thus the rays of light from the lamp entering the plate *a* through the walls of the aperture *c* will travel in all directions from the aperture *c* toward the edges of the plate, from which, since the edges are silvered, the rays reaching the edges will be reflected back into the body of the plate. If the edges be clear, the rays reaching them will pass out of the plate, but such will not cause any glare since the edges of the plate are masked by the walls of the recess in the instrument board in which the plate is positioned.

As explained above, rays of light from the lamp *d* are caused to travel through the body of the plate toward its edge, some directly and others due to reflection from face to face of the plate, the result of striking the faces at an angle of total reflection. Cer-

tain of the rays traveling directly through the body of the plate will strike the walls of the recesses *j* and *j''* and will pass out of the body of the plate and in passing from a dense to a lighter medium will by refraction be directed toward the convex bottoms *k*, *k'* of the recesses from which the rays will be reflected on to the dials of the instruments *l*, *o* and *p*. Other rays reflected from face to face of the plate will reach the surface of the convex bottoms of the recesses at an angle at which they will be refracted rather than reflected thereby and such rays will pass out of the body of the plate and be directed toward the dials of the instruments, or pass back into the body of the plate through the walls of the recesses. Those rays which pass out of the body of the plate from the walls or bottom of the recesses will be directed toward the dials of the instruments and will adequately and efficiently light them up, without causing any glare from the front of the plate through the front surface of which no rays pass out.

The walls and bottoms of the recesses *j''* act to direct the light rays striking them in the same manner as do the walls and bottoms of the recesses *j* and *j''* and since the depth of the recesses *j''* is greater than the depth of the recesses *j'*, which lie between recesses *j''* and the light, ample light will pass through the body of the plate between the bottoms of recesses *j'* and the front surface for an adequate lighting of the instruments *m* and *n*. Further light will reach the walls of the recesses *j''* by reflection from the edge of the plate, if it be made reflective, as by silvering.

It will now be observed that by virtue of my invention, the instruments carried by an instrument board of an automobile may be efficiently and, if desired, brilliantly lighted without the production of the slightest glare from the surface thereof.

It will be understood that I do not intend that my invention shall be limited in scope to the details of construction of the embodiment thereof above described, since it will be obvious that various modifications may be made without departing from the spirit of my invention. It will be understood that the light rays may be introduced into the body of the plate *a* at more than one point or through an edge thereof and that the several recesses in the plate may be of the same depth or a single recess may be provided for the accommodation of a plurality of instruments, and it will also be understood that the angularity of the walls of the recesses and the form of the bottoms may be varied so long as variations does not result in the refraction of light from the front face of the plate.

Having now fully described my invention,

what I claim and desire to protect by Letters Patent is:—

1. In an instrument board for automobiles, in combination, a sheet of glass having a plurality of recesses of varying depth formed therein, instruments supported adjacent to and facing the open ends of said recesses, an aperture in said sheet the walls of which adjacent the front and back surfaces of said sheet extend at an angle to the intermediate portion thereof, and a lamp positioned in said aperture.
2. In an instrument board for automobiles, in combination, a sheet of glass having a plurality of recesses of varying depth formed therein, instruments supported adjacent to and facing the open ends of said recesses, an aperture in said sheet the walls of which adjacent the front and back surfaces of said sheet extend at an angle to the intermediate portion thereof, a lamp positioned in said aperture and means for masking said lamp to prevent rays of light therefrom from extending from the front face of said sheet.
3. In an instrument board for automobiles, in combination, a sheet of glass having a plurality of recesses of varying depths formed therein, instruments supported adjacent to and facing the open ends of said recesses, a circular aperture the wall of which is tapered outwardly from points spaced from the front and back faces of said sheet, a lamp positioned in said aperture and means for masking said lamp to prevent rays of light therefrom from extending from the front face of said sheet.
4. An illuminating means for an object, comprising a transparent sheet having its rear face placed in front of the object and through which the object may be viewed, a source of light, a transverse surface of said sheet positioned so that rays from said source of light may pass through said transverse surface into the sheet and between the faces thereof, and means for directing some of said rays passing through said sheet upon the object.
5. An illuminating means for an object, comprising a transparent sheet through which the object may be viewed having its rear face in front of the object, means for projecting rays of light through the sheet and between the faces thereof at such angles that projected rays which strike the front face of the sheet in front of the object will be totally reflected into the sheet from said front face, and means for directing rays passing through said sheet upon the object.
6. An illuminating means for an object, comprising a transparent sheet through which the object may be viewed having its rear face in front of the object, means for projecting rays of light through the sheet and between the faces thereof at such angles that projected rays strike the front face of the sheet in front of the object at angles of incidence not substantially less than the critical angle, and means for directing rays passing through said sheet upon the object.
7. An illuminating means for an object comprising a transparent sheet through which the object may be viewed having its rear face in front of the object, means for projecting rays of light through the sheet and between the faces thereof, said sheet having a surface between the planes of its front and rear faces for directing rays passing through the sheet upon the object.
8. An illuminating means for a plurality of objects, comprising a transparent sheet through which the objects may be viewed having its rear face in front of the objects, means for projecting rays of light through the sheet in paths extending in the direction of its faces, said projecting means being located in alignment with the objects, intercepting means for directing some of said rays upon the object nearer to the projecting means, and means for directing rays not intercepted by the said intercepting means upon the object farther from the projecting means.
9. An illuminating means for an object, comprising a transparent sheet through which the object may be viewed having its rear face in front of the object, means for projecting rays of light through the sheet and between the faces thereof, and means located between the planes of the faces of said sheet to intercept rays passing through the sheet and direct them upon the object.
10. An illuminating means for an object, comprising a transparent member, through which the object may be viewed in front of the object, said transparent member having a plane front face and a rear face, portions of which rear face in front of the object form acute angles with the plane of the front face, and means for projecting rays of light upon the portions of acute angle of said rear face whereby they are reflected upon the object.
11. An illuminating means for an object, comprising a transparent sheet through which the object may be viewed having its rear face in front of the object, means for projecting rays of light through the sheet and between the faces thereof, means located between the planes of the faces of said sheet to intercept rays passing through the sheet and direct them upon the object, and means for reflecting rays at transverse edges of the sheet back through the sheet.
12. An illuminating means for an object, comprising a transparent sheet through which the object may be viewed having its rear face in front of the object and having a transverse convex edge portion, means for projecting rays of light through the sheet and between the faces thereof, means located between the planes of the faces of said sheet

to intercept rays passing through the sheet and direct them upon the object, and means for reflecting rays at the transverse convex edge portion back through the sheet.

5 In testimony of which invention, I have hereunto set my hand, at Philadelphia, Penna., on this 7th day of February, 1927.

FRANCIS I. DU PONT.
